DESIGN FOR A WOMAN'S HAT FRAME

Herbert Bentley, New York, N. Y.

Application September 10, 1946, Serial No. 133,230

Term of patent 14 years

(Cl. D3—13)

To all whom it may concern:

Be it known that I, Herbert Bentley, a citizen of the United States, residing at New York city, in the county and State of New York, have invented a new, original, and ornamental Design for a Woman's Hat Frame, of which the following is a specification, reference being had to the accompanying drawing, forming part thereof.

Fig. 1 is a top plan view of a woman's hat frame, showing my new design.

Fig. 2 is a side view thereof.

Fig. 3 is a front view thereof.

I claim:

The ornamental design for a woman's hat frame, substantially as shown.

HERBERT BENTLEY.
